UNITED STATES PATENT OFFICE.

FRANKLIN CHATFIELD, OF MINNEAPOLIS, MINNESOTA, ASSIGNOR TO NORTHWESTERN
KNITTING COMPANY, OF MINNEAPOLIS, MINNESOTA, A CORPORATION.

ATTACHMENT FOR SHELL-STITCHING MACHINES.

1,144,810.

Specification of Letters Patent. Patented June 29, 1915.

Application filed January 2, 1912. Serial No. 669,082.

To all whom it may concern:

Be it known that I, FRANKLIN CHATFIELD, of Minneapolis, Hennepin county, Minnesota, have invented certain new and useful 5 Improvements in Attachments for Shell-Stitching Machines, of which the following is a specification.

My invention relates to devices for inserting ribbons between the shell or chain 10 stitches and the edge of the fabric. These ribbons are usually fed between the stitches 15 and the garment under the presser foot of the machine and considerable time is required to insert the ribbon in the proper 20 position for feeding and there is always considerable danger of the ribbon being 25 caught and sewed fast. I have also found that considerable time was wasted in removing the ribbon from the feeding position when it was desired to form the shell 30 stitch without the ribbon and reinserting the ribbon when a part of the garment was reached where its use was desirable.

The object, therefore, of my invention is 35 to simplify and expedite the operation of placing the ribbon in position to be fed between the shell stitches and the fabric, or setting it in a position where the stitches will be formed without the ribbon.

Other objects of the invention will appear 40 from the following detailed description.

The invention consists generally in various 45 constructions and combinations, all as hereinafter described and particularly pointed 50 out in the claims.

In the accompanying drawings forming 55 part of this specification, Figure 1 is a front view, partially in section, of a portion of a shell stitching machine with my invention applied thereto, Fig. 2 is a plan view, partially in section, showing the relative position of the parts, Fig. 3 is a sectional view on the line $\alpha-\alpha$ of Fig. 1, Fig. 4 is a side view of a shell stitching machine and the 60 attachment applied thereto, showing the ribbon guide in its operative position, Fig. 45 5 is a similar view, showing the guide in its inoperative position, Fig. 6 is a detail sectional view, showing the mechanism for operating the ribbon guide, said guide being 65 shown in its working position, Fig. 7 is a similar view, showing the guide in its inoperative position. Fig. 8 is a detail plan view 70 of the chaining finger, Fig. 9 is a plan view 75 showing the parts in their working position 80

to insert the ribbon in the shell stitch, Fig. 10 is a detail sectional view, illustrating the adjustment of the fabric guide in position to increase the depth of the bight of the 85 stitches.

In the drawing, 2 represents the frame of the machine, and 3 the work table. 4 is a needle, 5 the presser foot and 6 the reciprocating hook which coöperates with the needle to form the stitch. These parts are 90 all in use with the ordinary shell stitching machine.

7 is a plate secured to the machine frame and 8 is a second plate between which and the plate 7 a guide-way is formed. In this 95 guide-way is a slide 10. A pin 11 is mounted in the plate 7 and projects into an opening 12 in the slide 10 in which a spring 13 is arranged. The tension of this spring normally tends to hold the slide in its retracted 100 position against the pin 11, shown in Fig. 10. A fabric guide 14 is mounted on the slide 10 and provided with a rearwardly projecting end 15 having a vertical slot 16 that is adapted to receive the laterally projecting pin 17 105 on the presser foot. This pin bridges the gap between the presser foot and the fabric guide and prevents the fabric and the fuzz thereon from entering this gap when the guide is set out, away from the presser foot 110 to increase the bight of the stitches. When the fabric guide is set up against the presser foot to decrease the bight of the stitches, the pin 17 will enter the slot in the guide. The tension of the spring 13 normally tends to 115 pull the guide away from the presser foot and by means of the mechanism hereinafter described the guide can be adjusted toward or from the presser foot against the tension of this spring until the desired bight of the 120 stitches is obtained.

Various devices may be employed for operating the fabric guide, but I prefer to provide the mechanism which I will now describe in detail. The plate 7 carries an outwardly projecting stud 18 supporting a sleeve 19 that is slidable on said stud and also adapted to rotate thereon and provided at its inner end with a seat 20 between which and a screw head 21 on the stud 18 a coiled 125 spring 22 is arranged. The tension of this spring is evidently increased by moving the sleeve outwardly on its supporting stud and decreased when the sleeve is pushed inwardly. A plate 23 is mounted on the inner 130

end of said sleeve and has a split lower portion provided with a clamp screw 24 for securing the plate 23 on said sleeve. The upper portion of said plate has a transverse slot 25 to receive a pin 26 that is carried by the slide 10 and projects outwardly through a slot 27 in the plate 8. When, therefore, pressure is applied to the pin 26 the slide 10 will be pushed outwardly to move the fabric guide toward the presser foot to change the bight of the stitches.

I make no claim to this fabric guide in this application, as it forms the subject of a companion application filed June 3, 1912, Serial No. 701,260.

For the purpose of moving the pin 26 I provide a sliding pin 28 movable lengthwise in a socket in the upper portion of the plate 23 and having one end contacting with the pin 26 and its opposite end engaged by a lever 29 that is fulcrumed at 30 and has a limited rocking movement. I prefer to provide a set screw forming a fulcrum for said lever to allow adjustment thereof and a locking screw 31 for holding the set screw in place. The outer end of the sleeve 19 has a finger grip 32 and upon said sleeve a collar 33 is mounted, having a finger grip 34. A pin 35 is mounted on said collar and projects between the lever 29 and the plate 23, so that when the collar 33 is rotated, the pin 35 will be pushed between the lever 29 and the plate 23 to rock the said lever and force the pin 28 inwardly against the pin 26, or withdrawn from engagement with the lever 29 to allow the fabric guide spring to withdraw the fabric guide from contact with the presser foot and increase the bight of the stitches, as shown in Fig. 10.

40 33' represents the ribbon guide, having one end adjustably mounted by means of the set screw 36 in the upper portion of the plate 23 and its opposite end provided with a cylindrical portion 37 into which the ribbon is threaded and guided thereby in a cylindrical form between the shell stitches and the edge of the fabric. A chaining finger 38 has a recess or depression 39 therein to receive the cylindrical portion 37 of the ribbon guide, as indicated in Fig. 6, so that the feed of the ribbon will be sufficiently low with respect to the chaining finger to prevent any possibility of the ribbon being caught by the hook 6 in the formation of the shell or chain stitch. This ribbon guide is capable of movement to an operative or inoperative position, as shown in Figs 6 and 7, by the adjustment of the sleeve 19 and the plate 23. I prefer to use 55 the plate chaining finger shown herein provided with the recess or depression, but obviously an opening or slot might be formed in the plate instead of the recess. The function of such slot or opening would be the same as the recess shown. This plate

23 is provided on its lower end with a lug 40 that is adapted to enter a notch 41 in a horizontal plate 42 that is secured to the plate 7. This notch has a beveled edge 43 with which the lug 40 contacts, as shown in Figs. 3 and 6. When the lug 40 enters the notch 41 the lower portion of the plate 23 will be rocked on the stud 18, throwing the upper portion of said plate toward the presser foot and tilting the ribbon guide to its proper ribbon feeding position, as shown in Fig. 2, the cylindrical portion of the guide resting in the recess 39. When it is desired to swing the ribbon guide to an inoperative position, the lug 40 is withdrawn from the notch 41 and allowed to slide along the edge of the plate 42 into the slot 44, the sleeve 19 sliding inwardly on the stud 18 and carrying the plate 23 with it and swinging the ribbon guide to an inoperative position, as indicated in Fig. 7. The ribbon can then be cut with a loose end of sufficient length for forming a bow.

With this device the ribbon guide is always threaded, the ribbon is supported close to the chaining finger ready to be set in an operative position to feed the ribbon within the chain stitch, and all the labor and annoyance of inserting the ribbon under the presser foot and the danger of having the ribbon caught by the stitch forming mechanism, is entirely avoided.

Furthermore, with this device the length of the loose ends suitable for tying a bow can be easily determined, and the ends made of uniform length.

I claim as my invention:—

1. In a stitching mechanism, a work table, a presser foot, and a chaining finger mounted in said work table beneath said presser foot and having a recess in its upper surface, and a guide fitting into said recess.

2. The combination, with a shell stitching machine, a work table, and a presser foot, of a fabric guide movable toward and from said presser foot, a chaining finger, a ribbon guide movable toward and from said chaining finger, and mechanism for operating said fabric guide and said ribbon guide simultaneously.

3. The combination, with a shell stitching mechanism, a presser foot and work table, of a fabric guide movable toward and from said presser foot, a movable ribbon guide, and mechanism for operating said fabric guide and said ribbon guide simultaneously or independently of one another.

4. The combination, with a stitching mechanism, a presser foot and work table, of a recessed chaining finger and a movable ribbon guide adapted to enter said recess.

5. The combination, with a stitching mechanism, of a recessed chaining finger, a movable ribbon guide having a part at one end to receive a ribbon and adapted to enter

said recess, said recess allowing said guide to feed the ribbon outside the path of said stitching mechanism.

6. The combination, with a shell stitching mechanism, of a plate having a sliding and rocking movement on its support, a ribbon guide carried by said plate, and means for operating said plate to move said guide to its operative or inoperative position.

10 7. The combination, with a shell stitching machine, of a stud projecting therefrom, a sleeve slideable on said stud, a spring mounted on said stud and normally tending to force said sleeve inwardly thereon, a plate secured to said stud and movable therewith, means engaging said plate for holding it and said sleeve against the tension of said spring, and a ribbon guide carried by said plate.

15 8. The combination, with a shell stitching machine, of a stud mounted thereon, a sleeve slideable on said stud, a spring carried by said stud and normally tending to force said sleeve inwardly thereon, a plate secured to said sleeve, a notched finger in the path of said plate, said plate and sleeve being capable of sliding lengthwise on said stud and rotating thereon to disengage said plate from said notched finger, a ribbon guide carried by said plate, said notched finger being adapted to hold said plate and ribbon guide in their working position against the tension of said spring, the disengagement of said plate from said finger by the movement of said sleeve allowing the tension of said spring to move said plate and guide to their inoperative position.

20 9. The combination, with a shell stitching mechanism including an upright needle, a presser foot and a horizontally reciprocating hook co-operating with said needle, of a part adjacent to said hook, said part having a recess therein, and a ribbon guide movable into and from said recess.

25 10. The combination, with a work table and presser foot, of a needle and hook device operating at an angle to one another to form a shell stitch, and means on said table adjacent to said needle and movable toward and from an operative position and operating to guide a ribbon out of the path of said hook.

30 11. The combination, with a machine frame, and a stitching mechanism, of a stud

mounted in said frame, a spring-pressed member having a sliding movement on said stud, a ribbon guide carried by said member and moved thereby from its inoperative to its operative position, and means for locking said member and guide in such positions.

35 12. The combination, with a frame and a stitching mechanism, of a sliding sleeve, a ribbon guide carried by said sleeve, the movement of said sleeve in one direction shifting said ribbon guide from an inoperative position to an operative position, and the movement of said sleeve in the other direction shifting said ribbon guide from an operative to an inoperative position, and a spring for normally holding said sleeve and guide in said latter position.

40 13. The combination, with a frame, and a stitching mechanism, of a stud mounted in said frame, a sleeve slideable thereon, a spring normally holding said sleeve at the limit of its inward movement on said stud, a member mounted on said sleeve, a ribbon guide having an angular arm mounted in said member and movable therewith, and means for locking said sleeve at the limit of its outward movement.

45 14. The combination, with a stitching mechanism, of a chaining finger having a recess or depression in its upper surface, and a movable guide fitting within said recess.

50 15. The combination, with a stitching mechanism and a presser foot and work table, of a chaining finger, and a ribbon guide fitting into said chaining finger and movable therein.

55 16. The combination, with a stitching mechanism and a presser foot, of a ribbon guide having a forward movement followed by a downward movement to its working position adjacent to said presser foot, said ribbon guide having an upward movement followed by a backward movement to retract it from its working position, and a chaining finger having an opening therein wherein said guide is movable.

In witness whereof, I have hereunto set my hand this 28th day of December, 1911.

FRANKLIN CHATFIELD.
